(57) **CLAIM**

The ornamental design for an earmuff user interface, as shown and described.

DESCRIPTION

FIG. 1 is a front perspective view of an earmuff user interface, showing my new design;

FIG. 2 is a front elevation view thereof;

FIG. 3 is a rear elevation view thereof;

FIG. 4 is a side elevation view thereof;

FIG. 5 is an opposite side elevation view thereof;

FIG. 6 is a top plan view thereof; and,

FIG. 7 is a bottom plan view thereof.

The broken lines shown in the drawings are only provided to illustrate the environment of the design, and form no part of the claimed design.

1 Claim, 4 Drawing Sheets(56)
